UNITED STATES PATENT OFFICE.

WILLIAM D. MCCOY, OF BROOKLYN, NEW YORK, ASSIGNOR TO THE NATIONAL CASH REGISTER COMPANY, OF DAYTON, OHIO, A CORPORATION OF OHIO.

CHECK ISSUING AND PRINTING MECHANISM.

Application filed September 6, 1919. Serial No. 322,235.

To all whom it may concern:

Be it known that I, WILLIAM D. McCoy, a citizen of the United States of America, residing at Brooklyn, New York, have invented a new and useful Check Issuing and Printing Mechanism, of which the following is a specification.

My invention relates to improvements in what are commonly termed cash registers.

10 The main object of the invention is to simplify the construction and operation of a machine of this character, enable it to be made of but few parts and to accomplish certain operations as more fully hereinafter set forth.

15 The mechanism as a whole is constituted so as to facilitate the carrying out of a system for identifying and tracing each separate transaction, that is, the record or detail strip and the checks as printed in the machine can always be located and compared with absolute certainty by reason of the simultaneously printed identification marks as hereinafter pointed out. Improvements 20 will be found to relate particularly to:

25 1st. Mechanism for printing the record of transaction upon a record slip and upon checks in which the consecutive numbering of the item on the record slip and on the checks is effected for each transaction.

30 2nd. Mechanism for printing the time and date of each transaction upon the checks.

35 3rd. Mechanism for feeding individual checks automatically to the printing position and delivering the same after the completion of the printing.

40 It will be obvious hereinafter that many of the details of construction may be varied in form and arrangement and substitution may be made within a wide range of equivalents without a departure from the spirit and scope of the invention claimed herein.

45 Fig. 1, is a front view of a machine embodying the improvements of my invention, part of the casing and the cash drawer being omitted, the setting arm and key being in its mid position.

50 Fig. 2 is a plan view of the mechanism shown in Fig. 1, the operating and setting arm being in its extreme left hand position and set for an amount of 95 cents.

55 Fig. 3, is a partial vertical section and elevation taken from the left of Fig. 1 and showing also a part of the cash drawer.

Fig. 4 is a plan view of the check printing 55 platen.

Fig. 5, is an enlarged vertical sectional view and side elevation, the parts being broken away and showing on an enlarged scale parts of the operating, registering and 60 printing mechanism.

Fig. 6 is a vertical sectional view of parts of the registering mechanism taken longitudinally of the operating knob.

Fig. 7, is a rear view of a fragment of the 65 operating knob showing the interlocking device.

Fig. 8 is a left-hand side view and elevation of part of the check printing and feeding mechanism in the position which the 70 parts occupy when the mechanism has been operated.

Fig. 9 is a perspective view of an inking roller and its supporting frame.

Fig. 10 is a front view and partial section 75 on the plane of the line A A of Fig. 6 showing details of the registering mechanism.

Fig. 11 is a similar section of the registering mechanism on the plane of the line B B of Fig. 6.

80 Fig. 12, is a detail side view of part of the mechanism for the carrying forward of dollars from the cents registering drum to the dollar registering devices.

85 Fig. 13, is a right-hand side view and partial section of the time clock and part of the printing mechanism.

90 Fig. 14, is a plan view and partial section of parts of the check and record strip printing mechanism.

95 Fig. 15 is a horizontal sectional view of parts of the check printing mechanism showing its connection with the time clock.

Fig. 16 is a detail perspective view of the cam for raising the platen to print the record 95 strip.

Fig. 17 is a bottom view of a check as printed and delivered from the machine.

Fig. 18 is an edge view of a plate for printing special matter.

100 Fig. 19 is a vertical front sectional view and projection of the check supply feeding mechanism.

Fig. 20 is a perspective view of the check discharging arm or "kicker."

105 Fig. 21 is a perspective view of the double pawl of Fig. 22.

Fig. 22 is a plan view showing the double

pawl and adjacent parts for compelling operation of the push key in the main setting arm.

Fig. 23 is a view of the under side of the 5 check feeding device.

Fig. 24 is a rear view and partial section of the record strip feeding and operating mechanism.

Fig. 25 is a perspective view of a fragment 10 of the check supply receptacle or magazine for containing the unprinted checks.

Fig. 26, is an upright sectional view of the same on the plane of the line E, E of Fig. 23.

In this case I particularly claim the check 15 supply, printing and delivery mechanisms, and cooperating mechanisms. Other features will be found claimed in my Patent 1,239,708 dated Sept. 11, 1917.

The parts 1, 2 and 3 together with the 20 vertical shaft 4 constitute the principal supporting members of the frame of the machine. The segmental section 5 of the front of the case is mounted on the bed-plate 6 which latter may serve as a portion of the 25 case for the usual cash drawer 7.

The main setting arm 8 is pivoted near the rear on the vertical shaft 4 and has a flange sleeve 9 at the front end. This sleeve 9 surrounds tube 10 which is mounted upon a hollow shaft 11 which carries the knob 12 at its front end. The segmental section 5 has a slot or opening 13 which guides the sleeve 9 and thus permits the main setting arm to be swung in a horizontal plane. A 35 guard 13' carried by the sleeve 9 covers the rear of the opening 13. The machine as herein illustrated is adapted to register and print amounts varying by five cents from 5¢ to 95¢ and dollars from zero to 19.

40 For the purpose of setting the mechanism I have arranged numerals zero 5, 10, 15, etc., to 95 along the upper beveled edge 14 of the segmental section 5 and numerals zero, 1, 2, 3, etc., to 19 around the beveled edge of 45 the knob 12. The former may be called "cents setting scale" and the latter the "dollar setting dial". It will be obvious however that the mechanism might be adapted to other systems of money counting and that 50 the cents setting scale might be arranged by units from zero, 1, 2, 3, etc., and that the dollar setting dial might be arranged for a larger or smaller amount. Normally the knob 12 is held against rotation by 55 means of the projection 15 at the rear which engages in a notch 16 in the flange sleeve 9 which is not rotatable. The knob however is adapted to be pushed inward, that is, to be left as viewed in Fig. 5 a distance 60 sufficient to disengage the projection 15 from the notch 16 and allow the knob 12 to be rotated. It will be noted that when the knob is rotated it cannot be pulled outward until it is rotated back to its normal position at which position the zero on the dollar 65

setting dial will be uppermost and adjacent the cents setting scale. The flanged sleeve 9 carries a stop 17 (Fig. 7) to prevent the knob 12 from being turned more than one complete revolution.

At its rear end the setting arm 8 has a projection 18 which is connected to a collar 19 pivotally mounted on the shaft 4 above the arm. This collar at its front end carries printing frame 19' for printing cents items. The collar 20 also pivotally mounted on shaft 4 carries printing frame 20' at the front end for printing dollar items. The collar 21 also pivotally mounted on the shaft 4 carries the operator's printing frame 21'. The frame 21 has a forward extension 55 provided with an operating knob or handle 56 so that the frame may be swung from right to left to set the operator's symbol for printing. Connected to the collar 20 is a segmental beveled gear 22 also pivoted on shaft 4 with which the bevel pinion 23 carried by the hollow shaft 11 is adapted to engage when the shaft and knob 12 are pushed to the rear, that is, to the left as 90 viewed in Fig. 5. A spring pawl 24 engages notches 25 in the upper face of gear 22 so as to assist in stopping the movement of the gear 22 at definite angular positions. A notched segment 26 beneath the setting arm 95 8 is adapted to assist in definitely positioning the setting arm when the reciprocating frame 27 is pushed inwardly as will be later described, it being necessary that a part of the frame 27 should mesh with one of the 100 notches in the segment 26 which notches correspond with the different cents amounts on the cents setting scale.

The rod 76 has a push key or thumb-piece 75 and is reciprocable in the hollow shaft 105 11 previously referred to as constituting a part of the main setting arm construction. A collar 77 securely fixed upon the rod 76 near its rear end engages an up-right portion 78 of the main reciprocating frame 27 110 which is carried by the main setting arm 8. The spring 79 has its rear end secured to the reciprocating frame 27 and its front end connected to a screw 80 or other projection carried by the main setting arm 8, so that the spring places a tension upon the reciprocating frame 27 to hold it in and to return it to its forward position, that is, at the right as viewed in Fig. 5. The rear lower portion of the reciprocating frame 27 has 115 an inclined or cam surface 81 adapted when the reciprocating frame is pushed inward to engage the corresponding inverted incline 82 on a vertically moving frame on a pillow block 72. When the push key 75 is 120 pushed inward the action of the incline 81 is to lift this vertically moving frame. When the up-right bolt portion 69 of the vertically moving frame is disengaged from the latch 73 (see Fig. 3) the drawer is released. 125

The arm 83 carried by the shaft 84 has a normally forward pressure exerted upon it by the spring 85. Near the lower end of this arm 83 is a roller 86 carried by the drawer 5. When the drawer has been released as just mentioned, the power of the spring 85 thus throws the drawer forward. The completion of closing the drawer will be described in connection with the printing operation hereinafter.

In order to prevent improper operation I have provided a double acting pawl device which necessitates the push key 75 being pushed completely inward and then thrown 15 completely forward by the action of the spring 79 and frame 27 when the key has been released (see Figs. 3, 5, 21 and 22). The body of the pawl device 87 is pivoted on a stud 88 carried by the reciprocating 20 frame 27. This has an elastic or spring portion 89 tending to hold the pawl device in the position shown in Fig. 21. The rear end of the pawl device has oppositely faced teeth 90, 91. Between them is arranged a 25 yielding or elastic projection 92. On the main setting arm 8 in the path of movement of the projection 92 is a cam member 93 having its opposite ends beveled as shown in Fig. 21. The opposite faces of the setting arm 8 adjacent this cam 93 having oppositely faced teeth 94, and 95 adapted to be engaged respectively by the teeth 90 and 91 of the pawl device. When the pawl device moves to the rear by reason of 30 the pushing in of the push key 75 and reciprocating frame 27 the elastic projection 92 engages the front end of the cam 93 and is forced to the left (as viewed in a plan view of the machine). This brings the teeth 35 of the pawl device into engagement with one of the teeth 95 in the main setting arm. The pawl device will yield sufficiently to allow the continued inward or backward movement of the operating key or pawl 40 device but will not allow forward or return movement until the projection 92 is disengaged from the rear of the cam 93. As soon as the projection is thus disengaged from the rear of the cam 93 the spring 89 will return the pawl device to its central 45 position so that the projection 92 will stand in the rear of the cam 93. If the push key is then released the action of the spring 79 will move the reciprocating frame 27 50 and the pawl tooth forwardly (to the right as viewed in Fig. 21). The rear end of the cam 93 will then be disengaged by the projection 92 and force the projection to the right (as viewed in plan view), thus tilting 55 the pawl device so that the tooth 90 engages one of the teeth 94 on the main setting arm. It will thus be seen that the pawl device and operating key are free to continue their forward motion but cannot be 60 pushed inward until the forward motion is 65

completed because of the inter-engagement of the tooth 90 with the teeth 94.

The registering mechanism is shown particularly in Figs. 2, 5, 6, 10, 11, and 12. A segmental bevel gear 100 which is stationary 70 is engaged by the teeth of a bevel gear 101. This latter has a hub 102 which is rotatably mounted upon the sleeve 103 on the hollow shaft 11. A star-wheel 104 carried by hub 102 is engaged by a roller 105 carried by a 75 pair of arms 106 which are normally pressed by a spring 107 so as to hold the roller 105 in one of the spaces between the teeth of the star-wheel 104. This roller 105 and its arms 106 are adapted to yield as the star-wheel 80 is rotated by reason of the lateral swinging of the main setting arm 8 and hollow shaft 11 but the tendency of the pressure of the roller 105 is to stop the rotation of the star-wheel 104 and consequently to stop the 85 swinging of the shaft 11 at one of the positions corresponding to one of the setting points on the cents setting scale. The sleeve 103 has a cam groove 108 in which a pin 109 on the reciprocating frame 27 projects. 90 The sleeve 103 is rotatable on the hollow shaft 11 but is prevented from rearward motion by the sleeve 110. When the key 75 is pressed inward and carries with it the reciprocating frame 27 as above mentioned, 95 the pin 109 by reason of its engagement in the cam groove 108 causes rotation of the sleeve 103 through nearly a complete revolution. The cents registering drum 111 is carried by a ratchet 112 which is rotatable 100 on the hollow shaft 11 (see Fig. 6). Mounted on the sleeve 103 is a plate 113 which is connected to the web of the bevel gear 101 by means of a spring 114. A spring pressed pawl 115 carried by the plate 113 engages 105 the teeth of the ratchet 112. Normally the spring 114 tends to rotate the plate 113 relative to the gear 101 until the projection 116 on the plate 113 engages the stop 117 on the gear 101. The gear 101 as above mentioned rotates as the arm is moved from left to right and vice versa and the position of the stop 117 is therefore dependent upon the position of the arm 8. The sleeve 103 has a flange 118 which has a 115 shoulder 119 which rotates with the sleeve 103 as the key is pushed in and out. The spring 114 normally tends to rotate the plate so that a part of it for instance, the hub of the pawl 115 presses against the 120 stop 119. As the key 75 is pushed inward the sleeve 103 is rotated to the right as viewed from the front or clockwise, by reason of the pin 109 in the cam groove 108 and the tension of the spring 114 will cause the 125 plate 113 and the pawl 115 to follow around to the right until the projection 116 on the plate 113 engages the stop 117 carried by the gear 101. The amount of the rotation of the plate and its pawl 115 will therefore 130

depend upon the angular position of the gear 101 and main setting arm 8. As the pawl 115 rotates to the right it slips over the teeth of the ratchet 112 and when 5 the key is released the pawl returns and rotates the ratchet 112 and the cents setting drum 111 through exactly the angle that the displacement of the stop 117 permitted the plate 113 and the pawl 115 to rotate when 10 the key was pushed inwardly. This then brings the proper number on the cents registering drum to the reading position which in this particular arrangement is selected to be at the upper surface of the drum. The 15 spring pawl 120 engaging with the notch or ratchet like periphery of the registering drum 111 prevents the drum from being turned backwardly (see Figs. 11 and 12).

Any suitable form of counting mechanism such as 121 may be employed for keeping track of the total number of dollars registered. This is driven by the plate 122 by the operation of the knob 12 and intermediate mechanism. Normally the plate 25 122 is held stationary by a projection or finger 123 carried by the reciprocating frame 27 engaging in a notch in plate 122 (see Fig. 10). The plate 122 carries a spring pressed pawl 124 engaging with the 30 teeth of the ratchet 125. The latter is pinned or otherwise suitably secured to a gear 126 which meshes with a pinion 127 on the shaft of the counting mechanism. On the rear end of the tube 10 previously 35 referred to is a plate 128 which is connected by means of a spring 129 to the hub of the plate 122. The tension of this spring holds the nose 130 of the plate 128 against the projection 131 carried by the plate 122. The 40 tube 10 has a flange at its front end carrying a pin 132 adapted to register with the recess 133 in the rear of the operating knob 12 when the knob has the zero on its dial uppermost. When the knob 12 is pushed 45 in (see Fig. 5) the pin 132 engages the recess 133 and thereupon the rotation of the dial 12 will be communicated to the tube 10 and the plate 128 on its rear end. The plate will thereupon be rotated through an angle 50 corresponding to the number of dollars of the item to which the dollar setting dial is set. The pinion 23 at this time is in mesh with gear 22 which is yieldingly held in position by means of the spring pressed 55 pawl 24 operating in conjunction with the notches 25 heretofore referred to. When the push key 75 is pushed inward and carries with it the reciprocating frame 27, the finger 123 is disengaged from the notch in 60 the edge of the plate 122 and passes to the rear leaving the plate 122 free to be rotated in a right hand direction as viewed from the front of the machine. In this right hand rotation caused by the tension of the 65 spring 129 the pawl 124 rides over the backs

of the ratchet teeth 125 until the rotation of the plate 122 is stopped by the engagement of the stop 131 with the nose 130 on the plate 128 which is the angular distance corresponding to the number of dollars of 70 the item set up. When the push key 75 is released the reciprocating frame 27 moves forward again and the finger 123 engages the teeth of the ratchet 134 on the rear of the plate 122, thus preventing the plate 122 75 from being rotated to a higher registration. When the knob 12 is rotated lefthanded back to the zero position the finger 123 rides over the back of the teeth of the ratchet 134 cut in the rear of plate 122 until it comes 80 opposite the notch in the edge of the plate 122 whereupon it engages and locks the plate. When the knob 12 and plate 122 are rotated backwardly as just mentioned, the pawl 124 being in engagement with the ratchet 125 rotates the ratchet and its attached gear 126 and the pinion 127 of the counting mechanism through angles corresponding to the dollar item which has been set up. It will be noted in this particular that by reason of the 85 interaction of the finger 123 on the reciprocating frame 27 with the teeth 134 on the back of the plate 122, the operation of the machine is completely locked until the knob 12 is turned backward to its zero position 90 and the registration set up has been completed. Until this takes place the machine cannot be further operated, since when the frame 27 is in this rearward position it is interlocked with the stationary notched 95 segment 26 previously referred to. 100

When the cents registering drum 111 has been advanced to 95¢ the next registration will carry forward or transfer the next item to the counting mechanism. Figs. 5, 105 6, 10, 11 and 12 show the details of this device. Beneath the drum 111 and plate 122 is located the short shaft 135 suitably pivoted on the main setting arm 8. At the rear end this shaft carries an upwardly projecting arm 136 which stands in the path of movement of the pin 137 which projects rearwardly from the drum 111. The front end of the shaft 135 carries a pawl arm formed in two parts 138 and 139 which are 110 pivotally connected together. A spring 140 exerts a pressure upon the two parts of the arm in connection with the shaft 135 so as to hold the upper end of the part 139 which is hooked as shown in Fig. 10 in engagement 115 with the teeth of the pinion 126 previously referred to. When the registering drum 111 moves forward from the 95¢ registering position to the zero position making a total of \$1.00 on the cents registering mechanism 120 the pin 137 strikes the arm 136 and moves it to the right as viewed from the front of the machine so as to rock the shaft 135 and arm 138 and carry the pawl part 139 to the 125 right. This rotates the ratchet 125 and the 130

5 gear 126 secured thereto and the latter being in engagement with the pinion 127 moves the dollar counting dial forward one point. As soon as the pin 137 is past the arm 136 the latter under the pull of spring 140 snaps back into its proper position ready for the carrying forward of the next dollar from the cents registering drum.

10 It will be noted that the cents registration occurs while the reciprocating frame 27 is being thrown forward by the spring 79 after release of the push key 75 and the dollar registration occurs while the knob 12 is being turned back to the zero position 15 of the dollar setting dial. As the carrying forward of the total of one dollar from the cents registration drum to the dollar registration device occurs when the cents registration takes place there is no possibility of 20 interference between the carrying forward operation and the regular operation of dollar registration from the operating knob.

25 The record or detail strip 145 is of any ordinary or suitable character and in the form shown is provided in a roll on the spool 146 and is wound on to the hub 147 traveling from left to right as viewed from the front of the machine (see Fig. 1). The hub 147 is hollow and mounted upon the 30 stationary spindle 148 (see Fig. 24). Secured to the hub is the ratchet 149 engaged by the spring pressed pawl 150. A vertically reciprocable member 151 (which also constitutes the printing platen for pressing 35 the record strip against the type) carries a spring finger 152 which is adapted to engage the teeth of the ratchet 149. A plate 153 has a portion cut away to provide a guiding and bearing surface for the end of the 40 spring finger 152 so that the member 151 rotates the ratchet 149 at about the middle of its downward stroke and the finger 152 is disengaged from the ratchet at the lower end of the stroke. On the upward motion 45 of the member 151 and finger 152 the ratchet is held from backward rotation by the pawl 150 and the finger 152 is retracted by the sliding engagement with the curved edge of the plate 153. The member 151 has a 50 shoulder 154 at the lower end engaged by the cam 155 (Fig. 16) whereby the member 151 is raised as will be pointed out, and is pressed downward by the spring 151^a (see Fig. 1).

55 The cam 155 is mounted upon the sleeve 156 which is rotatable in suitable bearings in the part 3 of the frame of the machine (see Figs. 14 and 15). In the particular form shown the cam is secured to the case 157 of the time 60 clock. The gear 158 rotatable with the cam and clock is in mesh with the segmental gear 159 which is secured on shaft 160 (see Fig. 13). This shaft 160 has an arm 161 connected by means of link 162 to the arm 65 163 on shaft 84 previously referred to (see

Fig. 3). The crank 164 on the right of the machine is secured to this shaft 84 and is normally nearly horizontal as shown in Figs. 1 and 3 being inclined slightly downward toward the rear. It should be noted 70 however that the particular position or angle or inclination of the crank is immaterial and the position is referred to simply for the sake of convenience of description. This crank 164 and the shaft 84 may be operated by any suitable driving means either 75 manual or power but for convenience I have illustrated the crank 164 with a handle for the purpose of operating the shaft 84.

80 In order to prevent errors and tampering with the machine I have provided means for necessitating the completion of the oscillation of the shaft 84 when once it has been started in either direction. This is illustrated in Figs. 1 and 2. Any suitable type 85 of full stroke device may be used, but as this mechanism forms no part of the present invention it will not be described in detail herein.

86 Normally the drawer 7 is closed and latched by the bolt 69 engaging with the latch 73 as before referred to. When the reciprocating frame 27 is pushed inward and raises the bolt 69 the latch 73 is released and the spring 85 secured to shaft 84 exerts its 90 pressure through the arm 83 and throws the drawer open at the same time raising the crank 164 and by means of the connection from the crank 163, link 162, crank 161, shaft 160, segmental gear 159 and pinion 158 95 rotates the cam 155 which lifts the platen member 151. As the cam rotates right-handed beyond the position shown in Fig. 13 the shoulder 154 is disengaged and the member is pulled downward by the spring 151^a 100 and the record strip is thus fed forward by the engagement of the finger 152 with the ratchet 149 which is secured to the winding hub. At the bottom of the stroke 105 the printing takes place as will be understood hereinafter. When the crank 164 is pulled forward and downward again it moves the arm 83 to the rear. This latter by its engagement with the roller 174 at the rear of the drawer closes the drawer and at 110 the same time releases the member 151 which is raised by the rotation of the cam 155 back to the position shown in Fig. 13 which is its normal position.

115 On the left of the pillow block 72 previously referred to is located a bolt 180 which has a limited forward and backward movement in or on suitable guides and is normally drawn forwardly by a spring 181 (see Fig. 3). The upright of the vertically 120 movable frame 71 on the pillow block is provided with a shoulder 182 adapted to engage the forward beveled end of the bolt 180 when the frame is raised by the action of the reciprocating frame 27. As the shoulder 182 125 130

passes above the bolt 180 the bolt snaps forward beneath the shoulder and thus prevents the frame from being moved down under the impulse of the spring 183 (see Fig. 13). The rear of the bolt 180 has a shoulder 184 or lip which projects to the left and is adapted to be engaged by the arm 83 when that is moved rearwardly by the downward action of the crank 164. As the arm 83 is moved to the rear the lip 184 is engaged by the arm and the bolt is retracted from beneath the shoulder 182 thus allowing the spring 183 and gravity to move the frame 71 downward. As the frame 71 moves downward the bolt 69 engages the catch 73 on the drawer and holds the drawer in its closed position. When the crank 164 is released the tension of the spring 85 rotates the shaft 84 until the arm 83 strikes the roller 86. It will thus be seen that the drawer 7 acts as a movable abutment for the arm 83. The bolt 69 serves to lock this movable abutment until the push key 75 is operated.

Normally the platen member 151 rests with its shoulder 154 upon the tip of the cam 155 as shown in Fig. 13. When the drawer 7, constituting the movable abutment as just mentioned, is released by the raising of the bolt 69 from the latch 73, the spring 85 turns the shaft 84 and the cam 155 through the medium of the mechanism above described. The cam thus rotates right-handed or clock-wise and the shoulder 154 of the platen member 151 is disengaged from the point of the cam, then drops to cause the printing, and is then gradually raised as the cam continues to rotate. The cam has its greatest radius at about the point 190 (see Figs. 13 and 16), which is somewhat greater than the radius of the cam at its tip directly beneath the shoulder 154 as shown in Fig. 13. A spring pressed catch 191 is adapted to snap beneath the shoulder 192 on the platen member 151 when the point 190 of the cam 155 raises the platen member to its highest position. The lower end of the catch 191 has a projection 193 at its rear whose upper and lower faces are inclined as shown in Fig. 13. An arm 194 carried by the vertically moving frame 71 has its front end beveled to co-act with the faces of the projection 193. When the frame 71 is moved upward upon inward travel of the reciprocating frame 27 the end of the arm 194 rides up the lower inclined face of the projection 193 and tilts the catch 191 until it comes above the upper inclined face of the projection 193, at which time the nose of the catch 191 is tilted to snap beneath the shoulder 192 on the platen member when the platen member is raised to its highest position by the high point 190 of the cam 155 coming beneath the shoulder 154. When the crank 164 is pulled forward and downward its first action is to oscillate the shaft 84 right-handed as viewed in Fig. 3 thus thrusting the rod 162 forward and oscillating the crank 161 and the shaft 160 left-handed as viewed in Fig. 3 and right-handed as viewed in Fig. 13 until the cam 155 is brought to the position shown dotted in Fig. 13 with the tip of the cam beneath the shoulder 154 on the platen member. Just at the completion of the downward forward movement of the crank 164 and the rearward movement of the arm 83 the lip 184 of the bolt 180 is engaged by the arm 83 and the bolt is retracted from the shoulder 182 on the vertically moving frame 71 which is at that instant forced downward by gravity and spring 183. The downward movement of the arm 194, by reason of the engagement of its forward beveled end with the projection 193 disengages the catch 191 from the shoulder 192 and permits the platen member 151 to be forced downward by the tension of the spring 151^a into the position shown in Fig. 13 with the shoulder 154 resting on the tip of the cam.

The frame 19' has a segment 200 with type faces on its upper surface for printing on the record strip the zero, 5, 10, 15, etc. cents items and which are arranged in a circumferential position corresponding with the location of the figures on the cents setting scale. The frame 20' has a similar type segment 201 with type faces along its upper surface of zero, 1, 2, etc., corresponding to the dollar setting dial figures. The frame 21' has a similar type segment 202 carrying the type for printing the operators' symbols in line with the dollar and cents figures. Nearer the front of the machine than the type segments just described are somewhat similar type segments carried by the same frames but having type facing downward for printing on the checks. The frame 19' carries a type segment 203 with the checks cents printing type. The frame 20' carries the segment 204 with the check dollar printing type. The frame 21' carries the segment 205 with the operator's symbol check printing type. These two sets of type segments are shown in front elevation Fig. 1 in plan view in Fig. 2, and section in Fig. 5. While the mechanism as previously described is provided with other alining mechanism I prefer also to provide additional means for insuring the perfect alinement of the type printing segments. For this purpose the segments 203, 204, and 205 are notched along their upper surfaces as shown in front view Fig. 1 and plan view in Fig. 2 in a manner similar to the notches of the gear segment 22 in Fig. 5 previously referred to. Above these segments adjacent the printing position is located a spring pressed plunger 206 adapted to engage in the notches in the upper surface of the type segments. The lower face of the plunger is beveled toward

5 gear 126 secured thereto and the latter being in engagement with the pinion 127 moves the dollar counting dial forward one point. As soon as the pin 137 is past the arm 136 the latter under the pull of spring 140 snaps back into its proper position ready for the carrying forward of the next dollar from the cents registering drum.

10 It will be noted that the cents registration occurs while the reciprocating frame 27 is being thrown forward by the spring 27 after release of the push key 75 and the dollar registration occurs while the knob 12 is being turned back to the zero position 15 of the dollar setting dial. As the carrying forward of the total of one dollar from the cents registration drum to the dollar registration device occurs when the cents registration takes place there is no possibility of 20 interference between the carrying forward operation and the regular operation of dollar registration from the operating knob.

25 The record or detail strip 145 is of any ordinary or suitable character and in the form shown is provided in a roll on the spool 146 and is wound on to the hub 147 traveling from left to right as viewed from the front of the machine (see Fig. 1). The hub 147 is hollow and mounted upon the 30 stationary spindle 148 (see Fig. 24). Secured to the hub is the ratchet 149 engaged by the spring pressed pawl 150. A vertically reciprocable member 151 (which also constitutes the printing platen for pressing 35 the record strip against the type) carries a spring finger 152 which is adapted to engage the teeth of the ratchet 149. A plate 153 has a portion cut away to provide a guiding and bearing surface for the end of the 40 spring finger 152 so that the member 151 rotates the ratchet 149 at about the middle of its downward stroke and the finger 152 is disengaged from the ratchet at the lower end of the stroke. On the upward motion 45 of the member 151 and finger 152 the ratchet is held from backward rotation by the pawl 150 and the finger 152 is retracted by the sliding engagement with the curved edge of the plate 153. The member 151 has a 50 shoulder 154 at the lower end engaged by the cam 155 (Fig. 16) whereby the member 151 is raised as will be pointed out, and is pressed downward by the spring 151^a (see Fig. 1).

55 The cam 155 is mounted upon the sleeve 156 which is rotatable in suitable bearings in the part 3 of the frame of the machine (see Figs. 14 and 15). In the particular form shown the cam is secured to the case 157 of the time 60 clock. The gear 158 rotatable with the cam and clock is in mesh with the segmental gear 159 which is secured on shaft 160 (see Fig. 13). This shaft 160 has an arm 161 connected by means of link 162 to the arm 65 163 on shaft 84 previously referred to (see

Fig. 3). The crank 164 on the right of the machine is secured to this shaft 84 and is normally nearly horizontal as shown in Figs. 1 and 3 being inclined slightly downward toward the rear. It should be noted 70 however that the particular position or angle or inclination of the crank is immaterial and the position is referred to simply for the sake of convenience of description. This crank 164 and the shaft 84 may be operated by any suitable driving means either manual or power but for convenience I have illustrated the crank 164 with a handle for the purpose of operating the shaft 84.

75 In order to prevent errors and tampering with the machine I have provided means for necessitating the completion of the oscillation of the shaft 84 when once it has been started in either direction. This is illustrated in Figs. 1 and 2. Any suitable type 80 of full stroke device may be used, but as this mechanism forms no part of the present invention it will not be described in detail herein.

85 Normally the drawer 7 is closed and latched by the bolt 69 engaging with the latch 73 as before referred to. When the reciprocating frame 27 is pushed inward and raises the bolt 69 the latch 73 is released and the spring 85 secured to shaft 84 exerts its 90 pressure through the arm 83 and throws the drawer open at the same time raising the crank 164 and by means of the connection from the crank 163, link 162, crank 161, shaft 160, segmental gear 159 and pinion 158 95 rotates the cam 155 which lifts the platen member 151. As the cam rotates right-handed beyond the position shown in Fig. 13 the shoulder 154 is disengaged and the member is pulled downward by the spring 151^a 100 and the record strip is thus fed forward by the engagement of the finger 152 with the ratchet 149 which is secured to the winding hub. At the bottom of the stroke 105 the printing takes place as will be understood hereinafter. When the crank 164 is pulled forward and downward again it moves the arm 83 to the rear. This latter by its engagement with the roller 174 at the rear of the drawer closes the drawer and at 110 the same time releases the member 151 which is raised by the rotation of the cam 155 back to the position shown in Fig. 13 which is its normal position.

115 On the left of the pillow block 72 previously referred to is located a bolt 180 which has a limited forward and backward movement in or on suitable guides and is normally drawn forwardly by a spring 181 (see Fig. 3). The upright of the vertically 120 movable frame 71 on the pillow block is provided with a shoulder 182 adapted to engage the forward beveled end of the bolt 180 when the frame is raised by the action of the 125 reciprocating frame 27. As the shoulder 182 130

- passes above the bolt 180 the bolt snaps forward beneath the shoulder and thus prevents the frame from being moved down under the impulse of the spring 183 (see Fig. 13).
- 5 The rear of the bolt 180 has a shoulder 184 or lip which projects to the left and is adapted to be engaged by the arm 83 when that is moved rearwardly by the downward action of the crank 164. As the arm 83 is moved to the rear the lip 184 is engaged by the arm and the bolt is retracted from beneath the shoulder 182 thus allowing the spring 183 and gravity to move the frame 71 downward. As the frame 71 moves downward the bolt 69 engages the catch 73 on the drawer and holds the drawer in its closed position. When the crank 164 is released the tension of the spring 85 rotates the shaft 84 until the arm 83 strikes the roller 86. It will thus be seen that the drawer 7 acts as a movable abutment for the arm 83. The bolt 69 serves to lock this movable abutment until the push key 75 is operated.
- Normally the platen member 151 rests with its shoulder 154 upon the tip of the cam 155 as shown in Fig. 13. When the drawer 7, constituting the movable abutment as just mentioned, is released by the raising of the bolt 69 from the latch 73, the spring 85 turns the shaft 84 and the cam 155 through the medium of the mechanism above described. The cam thus rotates right-handed or clock-wise and the shoulder 154 of the platen member 151 is disengaged from the point of the cam, then drops to cause the printing, and is then gradually raised as the cam continues to rotate. The cam has its greatest radius at about the point 190 (see Figs. 13 and 16), which is somewhat greater than the radius of the cam at its tip directly beneath the shoulder 154 as shown in Fig. 13. A spring pressed catch 191 is adapted to snap beneath the shoulder 192 on the platen member 151 when the point 190 of the cam 155 raises the platen member to its highest position. The lower end of the catch 191 has a projection 193 at its rear whose upper and lower faces are inclined as shown in Fig. 13. An arm 194 carried by the vertically moving frame 71 has its front end beveled to co-act with the faces of the projection 193. When the frame 71 is moved upward upon inward travel of the reciprocating frame 27 the end 55 of the arm 194 rides up the lower inclined face of the projection 193 and tilts the catch 191 until it comes above the upper inclined face of the projection 193, at which time the nose of the catch 191 is tilted to snap beneath the shoulder 192 on the platen member when the platen member is raised to its highest position by the high point 190 of the cam 155 coming beneath the shoulder 154. When the crank 164 is pulled forward and downward its first action is to oscillate the
- shaft 84 right-handed as viewed in Fig. 3 thus thrusting the rod 162 forward and oscillating the crank 161 and the shaft 160 left-handed as viewed in Fig. 3 and right-handed as viewed in Fig. 13 until the cam 155 is brought to the position shown dotted in Fig. 13 with the tip of the cam beneath the shoulder 154 on the platen member. Just at the completion of the downward forward movement of the crank 164 and the rearward movement of the arm 83 the lip 184 of the bolt 180 is engaged by the arm 83 and the bolt is retracted from the shoulder 182 on the vertically moving frame 71 which is at that instant forced downward by gravity and spring 183. The downward movement of the arm 194, by reason of the engagement of its forward beveled end with the projection 193 disengages the catch 191 from the shoulder 192 and permits the platen member 151 to be forced downward by the tension of the spring 151^a into the position shown in Fig. 13 with the shoulder 154 resting on the tip of the cam.
- The frame 19' has a segment 200 with type faces on its upper surface for printing on the record strip the zero, 5, 10, 15, etc. cents items and which are arranged in a circumferential position corresponding with the location of the figures on the cents setting scale. The frame 20' has a similar type segment 201 with type faces along its upper surface of zero, 1, 2, etc., corresponding to the dollar setting dial figures. The frame 21' has a similar type segment 202 carrying the type for printing the operators' symbols in line with the dollar and cents figures. Nearer the front of the machine than the type segments just described are somewhat similar type segments carried by the same frames but having type facing downward for printing on the checks. The frame 19' carries a type segment 203 with the checks cents printing type. The frame 20' carries the segment 204 with the check dollar printing type. The frame 21' carries the segment 205 with the operator's symbol check printing type. These two sets of type segments are shown in front elevation Fig. 1 in plan view in Fig. 2, and section in Fig. 5. While the mechanism as previously described is provided with other alining mechanism I prefer also to provide additional means for insuring the perfect alinement of the type printing segments. For this purpose the segments 203, 204, and 205 are notched along their upper surfaces as shown in front view Fig. 1 and plan view in Fig. 2 in a manner similar to the notches of the gear segment 22 in Fig. 5 previously referred to. Above these segments adjacent the printing position is located a spring pressed plunger 206 adapted to engage in the notches in the upper surface of the type segments. The lower face of the plunger is beveled toward 130

the right and toward the left to correspond with the beveled faced notches in the type segments 203, 204 and 205 so that the plunger will find its proper seat in the notches and 5 yet will allow the frames to be swung properly from side to side without too great resistance.

The inking ribbon is fed back and forth from one spool to another, the spools being of suitable character and mounted upon the shafts 10 210 and 211 (see Fig. 5). The ribbon 212 passes over the faces of the type segments 200, 201, 202 around the guide roller 213 at the rear, under the edge of the plate 214 15 and forward beneath the faces of the type on the segments 203, 204, 205 to the spool on shaft 211. The shafts 210 and 211 have ratchets 215, 216 respectively with teeth facing in opposite direction, for instance, (see 20 Fig. 8). An arm 217 pivoted at 218 carries two yielding pawls 219 and 220 adapted to cooperate respectively with the ratchets 215 and 216. On the end of shaft 160 opposite the oscillating segment 159 is another 25 oscillating segment 221. The pawl arm 217 is held in the position shown in Figs. 5 and 8 against the stop 222 by the spring 223. This pawl arm has a shoulder 224 adapted to be engaged by the nose 225 on the oscillating segment 221 when the latter is thrown 30 into the position shown in Fig. 8 by the release of the drawer and the upward and backward movement of the operating crank 164. This oscillates the pawl arm 217 on 35 its pivot 218 in a left-handed direction so that the pawl 220 rotates the ratchet 216 and thus winds up the ribbon on the lower forward spool shaft 211. When the operating crank 164 is pulled forward and downward 40 and the oscillating segment 221 is moved from the position of Fig. 8 back to the position of Fig. 5 the pawl arm projection 224 is released and the spring 223 pulls the pawl arm back against the stop 222, the pawl 220 45 yielding over the backs of the ratchet teeth 216. The pawl arm 217 carries a reversing member having two arms 226 and 227 adapted to be engaged by the ribbon on the winding spools when one or the other spool, as 50 the case may be, becomes filled. The pawl devices and reversing devices are pivotally mounted on the pin 228 (see Figs. 5 and 8). The tongue 229 on the pawl arm projects into a slot on the reversing device so 55 that the pawl and reversing devices are virtually secured together and have a common pivotal support on the arm 217. The pawl arm 217 carries a catch 231 with two notches adapted to be engaged by the tooth 60 232 on the reversing device. The catch 231 is pressed forward by a spring 233. When the lower ribbon spool becomes filled the pressure of the ribbon against the reversing arm 227 tilts the reversing device until the

tooth 232 snaps from the upper to the lower 65 notch in the catch 231 thus throwing the pawl 220 out of engagement with the ratchet 216 and throwing the pawl into engagement with ratchet 215. Continued movement of the mechanism causes the ribbon to be fed 70 in the opposite direction and wound upon the upper ribbon spool on shaft 210. The tongue 229 projects sufficiently to serve as a handle to effect the reverse movement, should such become necessary. 75

In order to provide a positive identification for the purpose of comparison between the checks and record strip I print on the successive checks consecutive numbers and adjacent each item on the record 80 strip I print the corresponding consecutive numbers of the same items. This is accomplished by means of two sets of counter wheels of suitable construction, having printing type upon their faces instead of 85 the ordinary visual display figures. These are shown particularly in Fig. 14. The printing wheels 235 are mounted on the shaft 236 which has a spring pressed arm 237 (Figs. 13 and 14) which is oscillated by 90 the projection 238 on the shaft 160 attached near the left-hand end thereof. On the shaft 236 or secured to the units wheel is a bevel gear 239 meshing with the lower face of the double faced miter gear 240 whose 95 upper face meshes with the gear 241 on the shaft of the printing wheels 242. The wheels 235 print on the upper face of the checks and the wheels 242 print upon the lower face of the record strip. The two sets 100 of wheels being geared together, rotate together and exactly the same numbers are printed upon the checks and upon the record strip. The part 243 of the platen 151 forces the record strip against the ribbon on the 105 type segments 200, 201, and 202 and the numbering wheels 242 for printing. 110

Figs. 5, 8, 13, 14 and 15 show the construction and arrangement of the dating and time printing mechanism while Fig. 17 shows the card or check 250 as it is printed on the bottom, the item being printed upon the upper surface. A series of printing wheels and segments are arranged on a common axis as shown in Figs. 14 and 15. 115 Wheel 251 carries the type face for printing the numbers of the days of the months as shown at 251' in Fig. 17. The segment 252 prints the words "Day of month" with a pointer as shown at 252'. The segment 253 prints an index or pointer 253' for months. The wheel 254 prints a scale of minutes and names of the months as shown at 254'. The segment 255 prints the pointer 255' to indicate the minute on the minutes scale. The 120 segment 256 prints the pointer 256' for indicating the hour on the hour scale. The wheel 257 prints a scale of hours a. m. and 125

p. m. as at 257 in Fig. 17. The pinion 260 on the hollow shaft 261 is driven by the oscillating segment 221 previously referred to which is in turn operated through the instrumentation of the movement of the arm 83 and shaft 84 and the link connection 162. The printing wheel 254 is secured to shaft 261 and rotates with it. The segment 253 is adjustably clamped to the shaft 261 in any suitable manner so that its angular position relative to the printing wheel 254 may be varied to bring its printing pointer opposite the proper month on the month's scale. This is set every month by hand. The printing segment 252 is securely clamped in any suitable manner upon the shaft 261 and prints the words "Day of month" and the pointer shown at 252 always in the same angular position so that it will come in the center of the check. The day printing wheel 251 is secured upon the sleeve 262 which is rotatably mounted in a part of the frame 3 and has a dial 263 at the left-hand side, which dial carries numbers corresponding to the numbers of the days of the months on the type wheel as shown in Fig. 12. A spider-like spring 234 presses against the dial 263 and the pinion 260 so as to frictionally hold the dial 263 and the printing wheel 251 in position. A stationary pointer 265 corresponds to the location of the pointer on the segment 252 when in its printing position, in order to set the dial 263 which is rotated in any suitable manner so that the number on the dial corresponding to the day of the month comes opposite the pointer 265. When thus arranged the corresponding number on the printing wheel 251 will be adjacent the pointer on the segment 252. This adjustment is effected when the drawer is closed and the parts of the mechanism are in their normal position.

Any suitable form of clock or time-piece is suitably mounted in the case 157. Preferably this clock is of the so called 24 hour type in which the hour shaft rotates once in each 24 hours. The minute shaft 237 of the clock serves as a centering and alining device for the time printing wheels and also carries the minute pointer printing segment 255. The hour shaft 238 is a hollow shaft as is customary in clock mechanism and carries the hour pointer printing segment 256. The hour number printing wheel 257 is carried by the sleeve 156 which is secured to the case of the clock. When the two pinions 158 and 260 are rotated simultaneously by their respective segmental gears 159 and 221 previously described, the printing wheels and segments and the time clock rotate together. The hour and minute index printing segments are rotated by the clock relative to the minute and hour print-

ing wheels so that the time of printing of each item is accurately recorded on the check.

The type wheels and segments just described are inked in suitable manner, for instance by means of an inking roller 270 (see Figs. 5 and 9) carried by a pivoted spring arm or frame 271. A suitable yielding roller 272 is rotatably mounted in the frame of the machine made for instance, of a yielding material so as to press yieldingly against the face of the printing wheels and segments and to constitute in conjunction therewith means for moving the check forwardly into a position to receive the imprint of the item and other characters as will be understood hereinafter.

The platen 275 for forcing the check up against the printing ribbon to receive the imprint of the item and other type is carried by two posts or plungers such as 276 secured to the platen in any suitable manner as for instance, in the recesses 277, 277 (see Fig. 4). These plungers 276 are pressed downwardly by suitable means as for instance, spring such as 278 (see Fig. 5) and held away from the printing ribbon. A suitable printing plate 214 (Fig. 5) may be secured to the under side of the web 273 (Fig. 14) to print advertisements upon the face of the check if desired. The narrow end 279 of the platen extends immediately beneath the item printing segments 203, 204, 205 previously described. The broad part of the platen 275 extends rearwardly beneath the web 273 for pressing the check against the bottom of the advertisement printing plate and the consecutive numbering printing wheels previously described. The plate 280 is beneath the platen 275 when the mechanism is in its normal position. The cam 281 on the shaft 160 is adapted to press against the plate 280 and the latter in turn lifts the platen 275 and forces it upward so as to print the upper face of the check. This cam 281 is secured in such an angular position upon the shaft 160 that it presses against the plate 280 and raises platen 275 at the very last part of the oscillation of the shaft 84 and after the feeding forward of the check has been completed so that the check is in its proper position on top of the platen 275.

The checks such as 250 are supplied in a magazine or chute 285 (see Figs. 19, 23, 25 and 26). The lower edges of the magazine are turned inwardly or flanged at 286 so as to support the edges of the checks. I have provided a tension or pressure device to force the checks down the magazine. A plate 287 rests upon the top of the pile of checks. This plate carries two pulleys or rollers 288 over which passes a flexible band or cord 290. One end of this is secured as at 291 in Fig. 25 and the other end is secured

to a spring winding drum 292 of any suitable character. In this way a substantially uniform pressure is maintained to hold the checks down in the magazine. The checks as they come below the edge 293 of the magazine are fed from the bottom of the magazine intermittently by a reciprocating feed device. The body consists of the plate 295 supported on the guides 296, 296 by means of a suitable anti-friction device which preferably consists of a series of balls such as 297 held in spaced relation by means of a perforated plate 298 through which the lower surfaces of the balls project. The engaging edge of the feed member is formed by the lip 299 which is a part of a spring device 300 secured to the lower part of the plate 295. In the rear end of this engaging member is a slot opening 301 in which a conical part 302 of a screw engages. By adjusting the screw in or out the conical surface by this engagement with the opening 301 will lower or raise the engaging lip 299 as the case may be in order to make it project above the plate 295 so as to correspond with the thickness of the check employed. A rack 304 pivotally secured to the feed plate 295 by means of the screw 305 engages the teeth of the pinion 260 when the parts are in their feeding relation, the rack being held yieldingly in engagement with the pinion by means of a spring 306. Normally the position of the check feed device is as shown in Fig. 5. When the movement of the reciprocating frame 27 releases the arm 83 as previously described and the segment 221 is oscillated, the check feeding device is moved to the rear until the bottom check of the stack is engaged at its rear edge by the feed lip 299. When the arm 83 is moved to the rear again by means of the operation of the crank 164 the feed device moves forward and carries the check 250 between the roller 272 and the time printing wheels. The continued rearward motion of the arm 83 rotating the time printing wheels moves the check forwardly on to the platen 275. After the operation of the platen 275 the check is discharged by a kicker 307. This kicker has its upper end slotted as shown in Fig. 20 so as to have a limited up and down movement on the screw or pivot bearing 308 and is under tension to be moved forward by means of the spring 223 previously referred to. The lower end of the kicker is provided with one or more teeth or other suitably formed engaging means such as 309. This kicker has a projection 310 at the left which is in the path of movement of the two pronged dog 311 pivotally carried by the oscillating segment 221. The dog is under the impulse of the spring 312 which presses it against stop 313 on the oscillating segment 211. When the segment is rotated right-handed as just above mentioned the upper prong of the dog snaps by the projection 310. When the segment is oscillated backward the dog engages the projection 310 on the kicker 307 and moves the latter to the position shown dotted in Fig. 8. The check is in the meantime being fed forward by the roller 272 and the time printing wheels and when the dog 311 snaps to the left past the projection 310 the kicker by reason of its engagement with the upper surface of the check is held in the rearward position until the check is released from the pressure of the platen which has in the meantime come into operation. When the platen 275 releases its pressure on the check the kicker is drawn forward by the tension of the spring 223 and the check is thus ejected from the machine. The check is guided between the parts of the frame 3, 3 so as to insure its being properly printed and delivered from the machine.

I have also provided mechanism by means of which the check feeding device may be thrown out of operation when desired. A reciprocating member 315 (Figs. 5 and 8) suitably guided in the frame of the machine has a handle portion 316 suitable for manual engagement by means of which the member 315 may be reciprocated. The rack 304 has a cam projection 317 adapted to be engaged by the nose 318 on the member 315. The spring frame 271 which carries the inking roller 270 has a projecting arm 319 in the slot 320 on the member 315. The plate 280 is pivotally carried by the member 315 being mounted upon the screw 321 so that when the cam 281 has operated as previously described the plate 280 will have a certain freedom of movement permitting the pressure of the cam to be transmitted to the platen 275. When the member 315 is in the position shown in Fig. 5 the check feeding and printing device is in the operative position but when the member 315 is drawn forward into the position shown in Fig. 8 the rack and the check feed plate are thrown out of operation, the inking roller 270 is retracted and the plate 280 is withdrawn from the path of movement of the cam 281. In these positions there can be no movement of the platen 275 or of the feed device and the printing wheels simply rotate idly back and forth. With the parts in the position shown in Fig. 8 in order to throw the check feeding and printing devices again into operation, the member 315 should be pushed to the rear when the drawer is opened otherwise a false timing relation would be established. I prefer however to disengage and engage the feed while the drawer is closed.

Any suitable form of stop device may be employed as is customary to prevent the drawer from being thrown out or accidentally removed from the case. The forward movement of the arm 83 is limited by the

length of the slot in the case 6 (see Fig. 3).

The transaction type wheel 370 (Fig. 5) is adjusted and the drawer releasing shaft 336 and cam 345 (Fig. 13) are operated by 5 means not shown in this application. For a description thereof and of parts not numbered, reference may be had to the patent hereinbefore referred to which discloses the invention herein claimed.

10 I claim:

1. The combination of a printing frame, means for setting said frame, a check supply magazine, means for individually feeding checks to printing position independently of 15 the movement of the printing frame and a platen for coacting with said printing frame.

2. In a machine of the character described, the combination of a printing frame, means for setting said frame, a check supply magazine, means for individually feeding checks to printing position independently of the 20 movement of the printing frame, a platen for coacting with said printing frame and means for rendering the check feed inoperative. 25

3. In a machine of the character described, the combination of printing mechanism including a movable platen, a check supply magazine having its lower end substantially 30 in line with the printing position, means for feeding checks individually from the bottom of the magazine directly to the printing position by a single operation of the machine and means for operating the platen.

35 4. In a machine of the character described, the combination of a movable printing device having type face, manipulative means for adjusting said device, a platen, means for operating the platen when the printing 40 device is stationary, a check supply magazine and means for individually feeding checks from said magazine to printing position between said device and said platen independently of any movement involving an 45 adjustment of said printing device.

5. In a machine of the character described, the combination of a movable printing device having type face, a platen, means for operating the platen when the printing 50 device is stationary, a check supply magazine, means for individually feeding checks directly from said magazine to printing position between said device and said platen and means for discharging the checks.

55 6. In a machine of the character described, the combination of movable type carrying frames adjustable to set up different amounts, a movable platen cooperating therewith, and means for feeding individual 60 checks to printing position between said frames and platen when said frames are stationary.

7. In a machine of the character described, the combination of a movable platen, a check 65 supply magazine, a check feeding means

provided to give a starting movement to an individual check in the supply magazine and feed same to printing position during a single operation of the machine and means for operating the platen.

8. In a machine of the character described, the combination of a movable platen, a check feeding means provided to give a starting movement to an individual check, rotary feeding means adapted to receive said check 70 and feed same to printing position, means for operating the platen and means for discharging the check.

9. In a machine of the character described, the combination of a check supply magazine, 80 a roller feed device, a slide for carrying individual checks from the magazine to the roller feed device, printing type, means for setting said type, and a platen cooperating with said type.

10. In a machine of the character described, the combination of a check supply magazine, a roller feed device, a slide for carrying individual checks from the magazine to the roller feed device, printing type, 90 means for setting said type, and a platen cooperating with said type, and means for disconnecting said slide.

11. In a machine of the character described, printing type and a platen, means 95 for moving one of said members toward the other for printing, a check supply magazine, a roller feed device for delivering checks to the printing position and means for intermittently selecting checks from the magazine and inserting them in the roller feed device.

12. In a machine of the character described, a record printing device, a check supply magazine, a check printing device, 105 mechanism for operating said printing device, means for feeding individual checks from the magazine to the printing position and means for throwing said feeding and printing mechanism out of operation.

13. In a machine of the character described, the combination of a check magazine, a printing wheel, means for feeding individual checks from the magazine to the printing wheel and means for rotating the 115 printing wheel and advancing an individual check thereby.

14. In a machine of the character described, the combination of a check magazine, a printing wheel, means for feeding 120 individual checks from the magazine to the printing wheel, means for rotating the printing wheel and advancing an individual check thereby and means for discharging a check.

15. In a machine of the character described, the combination of a rotary printing device adapted to print on one side of a check, a type frame transversely movable to said device and adapted to print on the op- 130

posite side of said check and means for feeding said check to printing position.

16. In a machine of the character described, the combination of a rotary check feeding device adapted to move a check forward, a type frame movable transversely to the direction of feed of said feeding device and adapted to print upon a check and means for contacting said type frame and 10 a check whereby the latter may be printed upon.

17. In a machine of the character described, the combination with the check supply magazine of a check feeding and print-

ing mechanism including, a printing wheel, 15 printing type and a relatively movable platen and an inking roller for the printing wheel and means for throwing the feeding, inking and printing mechanism out of action.

18. In combination, a type carrier having oppositely facing type, platens for engaging said type, said platens and type carrier being relatively laterally movable for adjusting said type in relation to said platens, and 25 means for moving said platens towards said type carrier for printing.

WILLIAM D. McCOY.
